(57) CLAIM

I claim the ornamental design for a kitchen pot filler faucet, as shown and described.

DESCRIPTION

FIG. 1 is a Perspective view of a kitchen pot filler faucet showing my new design;

FIG. 2 is other Perspective view of the kitchen pot filler faucet as shown in FIG. 1;

FIG. 3 is a Right-side view of the kitchen pot filler faucet as shown in FIG. 1;

FIG. 4 is a Left-side view of the kitchen pot filler faucet as shown in FIG. 1;

FIG. 5 is a Front view of the kitchen pot filler faucet as shown in FIG. 1;

FIG. 6 is a Back view of the kitchen pot filler faucet as shown in FIG. 1;

FIG. 7 is a Top view of the kitchen pot filler faucet as shown in FIG. 1; and,

FIG. 8 is a Bottom view of the kitchen pot filler faucet as shown in FIG. 1.

The broken lines are for the purpose of illustrating portions of the article that form no part of the claim.
